COIN SLIDE

Herbert G. Breitenstein, Chicago, Ill., assignor to
Raymond T. Moloney, Chicago, Illinois

Original application September 7, 1933, Serial No.
688,428. Divided and this application October
23, 1934, Serial No. 749,573

6 Claims. (Cl. 194—101)

The invention relates to an improved coin slide and particularly to a spurious coin ejector therefore, this application being a division of my co-pending application, Serial Number 688,428, filed

5 September 7, 1933, for coin slides.

The primary object of the invention is to provide a simple, inexpensive, foolproof coin slide which will release an associated coin controlled game, vending machine, or other mechanism, only 10 when an authorized coin is handled by the coin slide. If an unauthorized coin is used the slide will not release the associated mechanism and the unauthorized coin will be ejected inside the box containing the coin release mechanism where 15 the slug or the like is removed from circulation and possible further attempts to use the same.

The general object of the invention is to prevent the slide from releasing the associated mechanism when coins not having the required 20 characteristics of value, thickness, diameter, and composition, such as requisite metal, are attempted to be passed through the slide. Also it is intended to prevent use of coins having an aperture, as certain perforated or apertured foreign 25 coins.

Briefly, the coin slide is conventionally mounted horizontally in the wall of a game or the like, said slide being accessible outside the game box to receive a coin in a coin pocket provided there- 30 in for that purpose, while the foolproof coin handling mechanism of the slide is inside the game box inaccessible to the player. The slide is slid- 35 ingly supported in a stationary guide to cause the slide to move along a straight line. If the coin is of the proper size it can be slid into the game box by the slide and providing it is non-magnetic such as our standard five cent piece, which we will 40 here consider to be the authorized coin, the slide can then be pushed home to its innermost position to effect release of the coin controlled mechanism. It is to be understood that the associated mechanism can only be released or unlocked when the slide has been moved substantially the full 45 distance of its stroke into the cabinet or box containing the mechanism to be released. Should the coin be magnetic, a magnet picks it up at an initial point of movement inward of the slide so that no coin is lodged in the coin pocket when 50 inward movement of the slide is continued. When the empty pocket reaches a certain point in its inward travel, a pair of spring pressed sliding plungers enter the pocket to lock the slide against further movement. When the operator releases his hand from the slide a spring pulls the slide 55 back to its starting position and on the way mech-

anism is operative to free the coin from the magnet and flip it to one side where it falls into the cabinet and is not returned to the player. If no coin is used a single spring pressed plunger is immediately operative after slight movement of the slide to engage the empty coin pocket and lock the slide against further inward movement. If a cardboard disk is employed, this same plunger would bite into the disk and stop the slide. Should an apertured coin be used, this 10 same plunger would be forced into the hole in the coin to stop the slide. Such coin, however, would be withdrawn with the slide because of its lodgement in the pocket where the player could get it back.

So much will suffice to give a general understanding of the purposes and structure of the slide. The invention is illustrated in detail in the accompanying sheet of drawing, wherein:

Figure 1 is a top plan view of the coin slide and 20 guide frame with which it is associated;

Figure 2 is a longitudinal central sectional view through the coin slide structure taken along the line 2—2 of Figure 1, looking in the direction of the arrows;

Figure 3 is a transverse cross sectional view 25 through the structure taken along the line 3—3 of Figure 1, looking in the indicated direction; and

Figure 4 is a similar cross sectional view taken 30 along the line 4—4 of Figure 1 looking in the direction indicated by the arrows.

For the sake of clearness, the cabinet or box of a game or vending machine, to which the slide is attached, has not been shown; also the mechanism to be released by the slide and its connection with the slide likewise have not been shown, as these things form no part of the invention, and in any event they are well understood in this art and therefore unnecessary to a complete understanding of the invention.

In the drawing, as shown, the slide comprises a plate 10 having a screw tapped boss 11 for securing in the desired way to a wall of the cabinet, said plate having formed therewith a horizontal guide 12 extending in front of, as well as in back of, the plate 10, it being understood that the portion of the guide rearward of the plate is inserted through a suitable slot in the cabinet wall closed by the plate. Thus the major portion 45 of the guide and all of the foolproof mechanism carried thereby, presently to be described, are located within the cabinet inaccessible to the operator. The guide 12 is thus stationary and rigidly mounted.

This guide 12 presents a flat horizontal surface as shown in Figures 1 and 2 formed outside or forwardly of the plate 10 with a small finger hole 13 and at an inner intermediate point with a larger coin drop hole 14. Outside the plate 10 the guide is depressed along its longitudinal median line as shown in Figure 2 to provide a longitudinal guide groove 15 which is continued as shown behind the finger hole 13 into the plate part of the structure. The rear, or inner end, of the guide, in which the coin drop hole 14 is formed is depressed and at its rear or inner end carries on its top surface a stop block 16 securely held in place by a screw bolt 17 or other suitable means. A spacer 18 is laid on the guide surface as shown in Figure 2 between its channeled edges, said spacer plate being held in place in any suitable manner. This spacer plate 18 is stationary and formed with a coin drop hole 20 in registration with the hole 14 heretofore described. The mid-portion of the guide frame just back of the plate 10 is open at 21 to save metal, such opening being relatively narrow so that a coin can be passed thereacross, by the hand pushed slide next to be described.

This slide is an elongated flat strip 22 resting slidably and horizontally on the guide surface and between its channeled edges, said slide 22 having a bent handle end 23 for ease of manipulation. This slide is longer than the guide and passes inwardly through the plate 10, over the spacer plate 18 on which it slides, and back to a point beyond the inner end of the guide frame. At its rear end the slide carries at its bottom a pin 24 to which is connected one end of a spring 25, said spring having its other end anchored to a pin 26 carried by the under side of the guide frame 12 adjacent the opening 21 as shown in Figure 2. It will be understood after the slide is pushed inwardly the spring serves to return the slide to normal starting position when released by the operator's hand.

At its forward end the slide 22 has a coin receiving pocket or opening 27 of the proper size, said opening 27 normally, or in the starting position of the slide being directly over the finger hole 13 in the guide. Further, the coin hole 27 is larger than the finger hole 13 so that the coin will be supported in the pocket by the guide and cannot fall through. Forwardly of the coin pocket opening 27 the slide has a central, longitudinally disposed short depression to form a nib or boss 28 that fits down and slides in the groove 15 to guide the slide in its longitudinal sliding movements. Just to the rear of the hole 27 the slide carries a downwardly extending guide block or pin 29 moving through the guide groove 15 formed in line with the plate 10 as shown in Figure 2.

Looking at Figures 1 and 2 it will be seen that a cross plate 31 is fastened to the side of the guide frame 12 while on its opposite side the guide frame has fastened thereto an upstanding block 32 interfitted with the cross plate 31 to hold the same securely in place, said plate or bar 31 being spaced above the slide 22 to permit the same to slide freely between said plate 31 and guide 12 as will be understood. In a vertical bore 34 formed in the bar 31 between its ends, is a centrally disposed plunger 35 having a lower beveled edge 36, said plunger being pressed downwardly by a flat spring 37 carried by the block 32, as shown.

Between the lightener hole 21 and the coin drop hole 14 the underside of the guide frame

12 carries a second cross bar or plate 38 as shown in Figures 2 and 4, said plate 38 being securely fastened at its ends to the edges of the guide frame. A block 39 is secured to this plate midway between its ends, said block having secured thereto, as shown, a transverse flat spring having curled ends 40 engaging and pressing upwardly a pair of plungers 41 similar to the plunger 35 heretofore described. These plungers 41 each pass up through bores formed in the guide 12 as shown in Figure 4 and are spaced so that when the empty coin hole 27 is in line both plungers are pressed into the empty hole and engage the same at transversely diametric opposite points, while the first plunger 35 engages said empty hole along the longitudinal diametric line of the hole.

As shown best in Figures 1 and 4 the top edges of the guide frame 12, above the plate 38 carry a plate 42, fastened to the frame by screws, said plate, as shown providing shoulders 43 at each edge between which is arranged, flatly, a magnet 44 held down by a clamp device 45. The legs of the horseshoe magnet extend forwardly toward the plate 10 a substantial distance beyond the front edge of the plate 42 and above the open guide frame and the slide 22 so that in the event a magnetic coin is advanced by the slide to this point, the magnet legs are instantly operative to pick up and catch such coin.

The longitudinal central portion of the slide 22 from adjacent the lug 29 back to a point near its rear end is formed with a slot 47 the end of which in the starting position stops against the block 16, said slot guiding along the sides 35 of said block as shown in Figure 1. Thus the block 16 serves to limit the forward sliding of the slide under the influence of the spring 25.

The means for laterally ejecting a magnetic spurious coin comprises a pivoted member 48 pivotally connected to a pin 49 mounted on the slide 22 adjacent its rear end. Said member 48 is disposed alongside the structure as shown in Figure 1 and has its front end bent to form a hook portion 50 which may normally lie over the slide between the front portion of the magnet and the block 31, as shown. This member is normally pressed into the full line position shown in Figure 1 by a spring 51. To accommodate the cross swinging movement of the hook 50 the adjacent corner of the plate 42 is rounded as at 52. Further the edge of the guide frame is cut away at 53 to provide a passage for movement of the hook 50 in and out in relation to the slide. The adjacent edge of the frame 12 carries a guide strip 54 as shown. The use and operation of the slide will now be described.

First we will assume an authentic coin, such as the five cent piece is employed. The coin is placed in the pocket 27 and thereupon the operator grasps the handle 23 and pushes the slide inwardly against the force of the spring 25. As the pocket 27 with the coin therein presents a flat surface it rides under the yielding front plunger 35 which is thus made inoperative by the presence of the coin. Similarly as the slide advances the pocket and coin, the latter passes by the magnet and the two rear plungers 41 which cannot function to stop the slide when a coin is in the pocket. As the coin moves along it finally reaches a position directly over the registering coin drop openings 20 in the spacer 18 and 14 in the guide frame. Thus the coin drops through, free of the slide, and as the slide has not advanced the full stroke, the associated

game or vending mechanism is released or unlocked. The user now releases his hand from the slide and the spring 25 is operative to return the slide to its initial starting position.

5. If it is attempted to move the slide in without any coin in the pocket 27 then the front plunger 35 is immediately pressed into the empty hole 27 to lock the slide.

If a cardboard disk is played, then the front plunger 35 again immediately is pressed into and scores or perforates the disk to lock the slide against further movement.

If a coin having a central aperture is played then again the front plunger 35 is forced thereinto to lock the slide against further movement. Such coin can only be moved as far as the plunger 35 and when the spring 25 pulls the slide back, such coin is returned to the player because it is pocketed in the hole 27 and must move back with the slide. The coin is removed by inserting a finger upwardly through the finger opening 13 in the guide frame.

If a magnetic coin is attempted to be used the slide 22 carries the coin past the dog 35 until it moves under the magnet 44 whereupon it is instantly picked up and held thereby. The inward movement of the slide 22 carries the element 48 with it causing the hook part 50 to be forced laterally out of the slide as it guides outwardly over the rounded corner 52. The end of the hook 50 now guides against the guide strip 54 to the dotted line position shown in Figure 1. The empty coin pocket next receives the plungers 41 to lock the slide 22 against further inward movement.

When the slide is now released by the operator the spring 25 pulls the slide 22 back and at the same time, as the member 48 is pressed inwardly by the spring 51 it is guided back along the strip 54 until the hooked end is pressed forcibly through the passage 53 where it strikes, hammer fashion, against the trapped coin and positively ejects the same from the magnet and slide in an obvious manner. Thus the return stroke or movement of the slide is utilized to operate the slug ejector.

From this detailed description it will now be seen that an improved coin slide or chute has been provided which achieves the desirable objects heretofore recited.

It is the intention to cover herein all such changes and modifications of the preferred form selected for this disclosure, which do not in material respects depart from the spirit and scope of the invention.

What is claimed is:

1. In a device of the character described, the combination of an elongated slide adapted to move a coin, a guide frame for the slide adapted to permit a full predetermined length of stroke when a coin is moved by the slide, a magnet mounted adjacent the frame and slide and adapted to take and hold a magnetic coin from the slide when such coin is moved by the slide in proximity to the magnet, a spring pressed plunger carried by the frame and adapted to lock the slide against further movement when the magnet holds the coin to prevent the full stroke of the slide, a spring pressed ejector movably mounted on the slide including a portion normally disposed over the slide, and stationary guide means for causing said ejector portion to move to a position away from over the slide when the slide makes its in stroke and to cause said portion to snap back to normal position over the

slide to eject the magnetic coin from the magnet and slide when the slide makes its return stroke.

2. In a device of the character described, the combination of an elongated slide provided with a coin receiving aperture, a guide frame for the slide adapted to permit a full predetermined length of stroke when a coin is in the aperture, a magnet mounted on the frame above the slide, said magnet being operative to lift a magnetic coin and hold it above the slide when the latter moves the coin under the magnet, a pair of laterally spaced spring pressed plungers carried below the frame and adapted to be pressed upwardly into the empty aperture to lock the slide if an attempt is made to move the slide after the magnet has picked up the coin, whereby to prevent the full predetermined length of stroke of the slide, a spring pressed member carried movably by the slide and including a portion normally disposed over the slide, guide means on the frame for causing said portion to be moved to a position away from over the slide when the slide makes its in stroke and to cause said portion to snap back to normal position over the slide to eject the magnetic coin from the magnet and slide when the slide makes its return stroke.

3. In a device of the character described, the combination of an elongated slide having a coin receiving aperture, a guide frame for the slide adapted to permit a full predetermined length of stroke when the slide aperture contains a coin, a magnet carried by the frame, said magnet being operative to take and hold a magnetic coin out of the aperture, lock means to prevent completion of the stroke under such circumstances, a spring to return the slide to its initial starting position, a resiliently urged member pivotally carried by the slide and embodying a bent end normally disposed across the slide, guide means on the frame for causing said bent end to be moved to a position away from across the slide when the slide makes its in stroke and to cause said bent end to snap back to normal position across the slide to eject the magnetic coin from the magnet and slide when the slide makes its return stroke.

4. In a device of the character described, the combination of an elongated slide having a coin receiving aperture, a guide frame for the slide adapted to permit a full predetermined length of stroke when the slide aperture contains a coin, a magnet carried by the frame, said magnet being operative to take and hold a magnetic coin out of the aperture, lock means to prevent completion of the stroke under such circumstances, a spring to return the slide to its initial starting position, a forwardly extending spring pressed member pivotally carried adjacent the inner or rear end of the slide, said member having a hooked end normally spanning the slide below the magnet, and means to guide the hooked end laterally of the slide when it is moved inwardly and to permit the hooked end to disengage a magnetic coin from the magnet when the slide is returned forcibly to eject such coin from the slide.

5. In a device of the character described, the combination of an elongated slide adapted to move a coin, a guide frame for the slide adapted to permit a full predetermined length of stroke when a coin is moved by the slide, a magnet mounted adjacent the frame and slide and adapted to take and hold a magnetic coin from the slide when such coin is moved by the slide in proximity to the magnet, a spring pressed piv-

oted ejector member carried by the slide and movable therewith, and a guide on the frame, said ejector member having a hooked end normally disposed over the slide and adapted to be moved by the guide to a position to one side of the slide on the in stroke of the slide, said ejector member having its hooked end moved across the slide by the guide to eject the magnetic coin from the magnet when the slide makes its return stroke.

6. In combination, a frame, a coin moving slide mounted on the frame for reciprocating

movement, a magnet associated with the frame adapted to pick up and hold a magnetic coin substitute on the inward stroke of the slide, a spring pressed hook shaped ejector member pivotally carried by the slide, and a guide along one edge of the frame, the hook portion of the said member riding along the guide laterally of the frame on the inward stroke of the slide, the return stroke of the slide causing said hook portion to snap across the slide to eject the magnetic coin held by the magnet from the slide.

HERBERT G. BREITENSTEIN.
